FIG. 1.

FIG. 2.

FIG. 3.

Inventor

H. M. Follweiler

By William J. Faehle

Attorney

UNITED STATES PATENT OFFICE.

HENRY M. FOLLWEILER, OF HAZLETON, PENNSYLVANIA.

RUBBER HEEL.

1,409,692.

Specification of Letters Patent. Patented Mar. 14, 1922.

Application filed October 11, 1921. Serial No. 507,042.

To all whom it may concern:

Be it known that HENRY M. FOLLWEILER, a citizen of the United States, residing at Hazleton, in the county of Luzerne and State of Pennsylvania, has invented certain new and useful Improvements in Rubber Heels, of which the following is a specification.

This invention has relation to certain new and useful improvements in a resilient heel and shank support and has for its primary object the provision of a device of this character which may be constructed in a single member comprising a heel portion and a tongue adapted to extend in a particular manner from the heel member and rest beneath the shank portion of the shoe to properly support the shank and form a resilient cushion therebeneath as well as providing a resilient cushion or support for the heel.

20 The invention has for another object the provision of a heel and shank support of the character stated which will be formed in such a manner as to properly support the arch and brace this portion of the foot of the wearer of the shoe having the combined heel and shank support applied thereto, relieving the shank of the strain to which it is usually subjected when the party is standing or walking.

25 The invention has for a further object the provision of a device of the character stated in which the shank supporting portion of the device will be positioned beneath the shank or raised portion of the shoe and out of the way and which will also be formed in such a manner as to engage the surface upon which the shoe is resting previous to engagement of the surface by the forward portion of the shoe or the heel, thereby permitting this shank supporting member to receive the weight of the body standing or walking either when the sole of the shoe is straight or when it is bent during the act of taking a step, thereby thoroughly and properly supporting the arch of the foot at all times.

30 The invention has for a still further object the provision of a device of the character set forth which will be effective in use by parties suffering from weak or fallen arches and bodies which are required to stand or walk a great portion of the day, as this device will thoroughly and properly support the foot and relieve the same of undue strain from continuous standing or walking.

With the foregoing and other objects in view as will appear as the description proceeds, the invention consists in the novel construction, combination and arrangement 60 of co-operating elements as hereinafter more specifically set forth, claimed and shown in the accompanying drawings forming a part of the present application and in which:

Figure 1 is a side elevation of a shoe of 65 conventional form with my invention applied thereto.

Figure 2 is a bottom plan view thereof.

Figure 3 is an elevation of the invention removed from the shoe.

Referring more in detail to the drawings in which similar reference characters designate corresponding parts throughout the several views, 1 indicates a heel member which may be formed similar to the shoe 75 heel 2 and which may be provided with a plurality of openings 3 for suitable securing members for the purpose of attaching this heel member 1 to the shoe heel 2, as is the usual practice in securing rubber heels 80 to the shoe heels. This heel member 1 is formed of a suitable grade of rubber or other resilient material and has projecting from its forward edge portion 4, the tongue or shank supporting member 5, as shown 85 clearly in Fig. 2. This member 5 is offset from the front of the edge 4 of the heel member 1, as clearly shown in Fig. 2, so as to lie beneath the inner side portion of the arch of the foot and resting in or extending 90 into the space beneath the raised or shank portion 6 of the sole 7 of the shoe 8, as clearly shown in Fig. 1 of the drawings. This member 5 has its upper and lower faces of 95 convex form as well as the side portions and connect with the heel member 1 by a reduced shank portion 9, the member 5 terminating in a forward pointed end 10 with the upper and lower edges converging gradually or concaved slightly, as shown in Figs. 1 100 and 3. By referring to Figs. 1 and 3 of the drawings it will be seen that the larger or central portion of the shank supporting member 5 has its upper and lower edges extended so as to completely fill the space beneath the shank portion 6 of the shoe and adjacent the heel 2, the lower portion of the member 5 extending below the front face of the heel member 1 and the ball or main portion of the shoe sole 7, causing the central 110 or enlarged portion of the shank supporting member 5 to contact with the surface as the

party wearing the shoe stands or walks, thereby pressing upwardly the shank portion 6 of the shoe and forming a resilient support for the arch portion of the foot 5 within the shoe 8. This will serve to resiliently support the wearer while either standing or walking, and in connection with the resilient heel member 1, will relieve the foot entirely of all unnecessary strain and 10 strengthen the arch of the foot. This device may be readily applied to a shoe and will be highly efficient in use, serving properly the purpose for which it is intended.

It is believed that the complete construction and operation of this device may now be 15 readily understood from the foregoing description taken in connection with the accompanying drawings and further detailed description is believed to be unnecessary.

20 While the preferred embodiment of the invention has been shown and described, it will be understood that minor changes in the details of construction and arrangement of parts may be resorted to within the scope 25 of what is claimed without departing from the spirit of the invention.

What I claim is:—

1. A resilient heel and shank support comprising a heel member adapted to be secured to a shoe heel, and a tongue extending from 30 one side of the forward edge portion of the

heel member and terminating in a reduced forward end, said tongue being connected with the heel member by a reduced neck portion, said tongue having its central portion of such thickness as to carry its upper edge to a point adjacent the shank portion of the shoe sole while its corresponding lower edge extends into a horizontal plane beneath the horizontal plane of the heel 40 member and the shoe sole.

2. A resilient heel and shank support comprising a heel member adapted to be secured to a shoe heel, and a shank supporting member extended from the forward edge of the 45 shoe member and offset from the center thereof towards the inner side of the shoe, said shank supporting member decreasing gradually in width and thickness toward its forward end and having a reduced neck portion connecting said member with the shoe heel, the shank supporting member being of such size that when the upper face thereof contacts with the shank portion of the shoe sole, the opposite lower face of the shank 55 supporting member extends into a horizontal plane beneath the horizontal plane of the lower edge of the shoe sole and the heel member mounted on the shoe heel.

In testimony whereof I affix my signature. 60

HENRY M. FOLLWEILER.
